(57) **CLAIM**

The ornamental design for ball chain clasp as shown and described.

DESCRIPTION

FIG. 1 is a top front isometric view of a ball chain clasp.

FIG. 2 is a bottom isometric view thereof.

FIG. 3 is a front side elevation view thereof.

FIG. 4 is a back side elevation view thereof.

FIG. 5 is a left side elevation view thereof.

FIG. 6 is a right side elevation view thereof.

FIG. 7 is top view thereof.

FIG. 8 is a bottom view thereof.

FIG. 9 is an environmental view showing the ball chain clasp attached to a ball chain; and,

FIG. 10 is a cross sectional view along line 10-10.

The features shown in broken lines in the drawing form no part of the claimed design. The broken lines showing of a ball chain in FIG. 9 is for the purpose of illustrating environmental structure and forms no part of the claimed design.

1 Claim, 9 Drawing Sheets
